 corporation of Ohio

Application August 30, 1937, Serial No. 161,563

49 Claims. (Cl. 62—5)

It is an object of this invention to provide a refrigerating system which will insure an adequate supply of ice blocks at all times.

It is another object of this invention to provide a refrigerating system which will provide a supply of ice blocks freely floating in a body of very cold water.

It is another object of this invention to provide a control mechanism for refrigerating systems which will control both the formation of ice 10 and the box temperature.

It is another object of this invention to provide a refrigerating system which is so controlled that the demand for freezing of ice takes precedence over the demand for box cooling.

It is another object of this invention to provide a refrigerating system which is self-defrosting at all times.

It is another object of this invention to provide a refrigerating system which maintains a high humidity in the storage compartment.

It is a further object of this invention to provide an evaporator having a plurality of sections which are arranged to perform distinct functions.

It is a further object of this invention to provide an evaporator having a plurality of sections one of which functions as a box cooler and the other of which functions as an ice freezing coil.

It is another object of this invention to provide a refrigerator wherein melted frost is automatically removed from the box.

It is another object of this invention to provide a refrigerating system having an evaporator composed of a plurality of sections which are selectively rendered operative.

Other and further objects of the invention will become apparent as the description proceeds when taken in connection with the accompanying drawings, in which:

Figure 1 is a diagrammatic view illustrating my invention applied to a three-fluid continuous absorption refrigerating apparatus.

Figure 2 is a sectional view taken along the line 2—2 of Figure 1 and looking in the direction of the arrows.

Figure 3 is a partial sectional view of a detail.

Figure 4 is a view illustrating a modification of the apparatus illustrated in Figure 1.

Figure 5 is a broken view on a smaller scale

showing the arrangement of the cooling elements and the water tank in the refrigerator cabinet.

Referring to the drawings and first to Figure 1 thereof, it will be seen that I have diagrammatically illustrated a continuous three-fluid absorption refrigerating system comprising a generator B, an air cooled rectifier R, a finned air cooled condenser C, an evaporator E, and an absorber A. These elements are suitably connected by various conduits to form a number of gas and liquid circuits and a complete refrigeration circuit.

The generator B comprises an outer liquid-retaining vessel 11 and an inner gas flue 12. The top portion of the space between the vessel 11 and the flue 12 forms a gas and liquid separation chamber. Refrigerant vapor, preferably ammonia, is discharged from the vessel 11 through a conduit 13 to the rectifier R wherein entrained water vapor is condensed. From the rectifier R the entrained water vapor flows backwardly into the generator B and the refrigerant vapor discharges into an air-cooled condenser C wherein it is liquefied. Liquid refrigerant is discharged from the condenser C through a conduit 14 into the evaporator E through which it flows counter to a stream of an inert gas, such as hydrogen or nitrogen, into which the liquid evaporates to produce refrigeration. The refrigerant vapor-gas mixture leaves the evaporator through a conduit 15 and enters the inner part of a gas heat exchanger 16. From the gas heat exchanger 16, the inert gas refrigerant vapor mixture passes through a conduit 17 into the bottom of an absorber A. The vapor-gas mixture passes upwardly through the absorber A in counterflow relation with weak absorption liquid supplied to the top of the absorber A by a conduit 18 connected to the generator B. The flow through the inert gas system is induced by the density difference between the column of cold rich gas leaving the evaporator and the column of warm weak gas leaving the absorber.

In the absorber A, the refrigerant vapor is absorbed in the absorption solution and the purified inert gas exits from the upper portion of the absorber through a conduit 19 which leads to the outer pass of gas heat exchanger 16. From the outer pass of the gas heat exchanger 16, the inert gas returns to the evaporator E through a

50

conduit 20. The conduit 20 is drained to the strong liquor reservoir in the bottom of the absorber A by means of a conduit 21. The gas return conduit 19 is drained to the conduit 21 by means of a conduit 22.

The strong absorption liquid which collects in the bottom of the absorber A is returned to the generator by way of a conduit 23 which is in heat exchange relation with the weak liquor conduit 18. The conduit 23 is coiled around a lower extension of the flue 12 as indicated at 24. This forms the primary heating portion of the generator due to the fact that the coil 24 is positioned immediately above a gas heating burner 25. Part of the refrigerant contained in the coil 24 is vaporized therein and functions to elevate the weakened liquid through the conduit 26 by the well known vapor lift action. The weak liquor and the refrigerant vapor are discharged into the separation chamber in the upper portion of the space between the flue 12 and the vessel 11.

The absorber A, which may be of any desired construction, may be cooled in any manner desired. As illustrated, the absorber is cooled by means of a conduit 27 which is coiled there-around and communicates at its upper end with a conduit 28 leading to an air-cooled bank of finned cooling tubes 29. The cooling tubes 29 communicate with the lower end of the coil 27 by means of a conduit 30. The heat absorbed by the coil 27 is transmitted to the fluid therein and a thermo-syphonic circulation occurs through the coil 27, conduit 28, cooling coil 29, and return conduit 30.

It is to be understood that the gas heat exchanger, absorber, condenser, and boiler are illustrated and described herein only in a general manner; these elements may partake of any desired particular construction.

Referring now to the evaporator, it will be seen that it comprises a box cooling coil 31 provided with a series of fins 32, only one of which is shown. The liquid refrigerant supply conduit 14 and the inert gas vapor mixture discharge conduit 15 both communicate with the upper end of the box cooling coil 31.

The lower end of the box cooling coil 31 communicates through a conduit 33 with an ice freezing coil. The ice freezing coil, as illustrated, comprises two laterally positioned sections consisting of upper and lower conduits. The near ice freezing section, as viewed in Figure 1, comprises an upper conduit 34 which is connected at its rear end to the conduit 33 and at its front end to a lower conduit 35 by means of a return bend. The rear end of the conduit 35 communicates with a transverse conduit 36 which communicates with the rear end of the upper conduit 37 of the remote ice freezing section, as viewed in Figure 1. The conduit 37 communicates at its forward end with a lower conduit 38 which opens into the gas supply conduit 20 previously described. The conduits 33, 34, 35, 36, 37, and 38 are sloped downwardly continuously from the vertical box cooling coil to the drain conduit 21 in order to permit gravity flow of liquid refrigerant therethrough.

The conduits 34 and 35 are suitably secured, as by welding, to a plurality of spaced freezing pads 39 which are preferably constructed from material having a relatively high heat conductivity. The ice freezing evaporator sections 37 and 38 are connected together by spaced ice freezing

pads 40 corresponding to the pads 39 previously described. The pads 39 and 40 are so arranged that they will snugly and slidably receive the tapered bottom plate 41 of a water tank 42. The tank 42 is designed to rest freely upon the pads 39 and 40, whereby it may be removed therefrom simply by lifting it upwardly or by sliding it forwardly in the refrigerating compartment.

The evaporator is intended to be arranged in 10 the center or near one side of the top portion of a refrigerating cabinet. The box cooling coil 31 is designed to be placed adjacent the rear wall of the cabinet with the ice freezing evaporator sections 34, 35, 37, and 38 projecting forwardly 15 therefrom.

The vessel 42 and the ice freezing portions of the evaporator may be placed in a housing constructed of insulating material in order that they may not affect, or be affected by, the condition of 20 the air in the refrigerating compartment. However, it is desirable to expose the contents of the tank 42 for reasons to be described hereinafter.

The control mechanism for the refrigerating system just described will now be explained. The burner 25 is supplied with fuel from a conduit 25 43. Flow of gas to the conduit 43 is controlled 44 by a solenoid gas valve 44. A pilot burner 46 is supplied with gas by a conduit 45 including a small regulating valve 46. Any suitable means 30 may be provided to stop the flow of gas in the event of complete flame failure at the generator B.

The box cooling coil 31 is completely enclosed 35 in a box 47 of insulating material. The upper and lower ends of the box 47 are closed by movable flap valves 48 and 49, respectively. The flap valve 48 is pivoted upon a suitable support at 50. The flap valve 49 is pivoted upon a suitable support at 51. The flap valves 48 and 49 are connected together by means of a rod 52 which is pivoted at 53 to the flap valve 48 on the right hand side of the pivot 50 as viewed in Figure 1, and is pivoted at 54 on the left hand side of the pivot 51 of the flap valve 49, as viewed in Figure 45 1. The flap valve 49 is provided with a rear extension, as viewed in Figure 1, which is pivotally connected at 55 to a vertically extending actuating rod 56. The arrangement is such that upward movement of the rod 56 causes both flap 50 valves to pivot about their respective pivots in opposite directions and thereby open the upper and lower ends of the box 47 whereby the air contained in the refrigerating compartment may 55 freely circulate therethrough and over the box cooling coil 31 and the fins 32. It will be seen that the flap valves move in opposite directions whereby they are mutually counterbalanced and require a minimum of power to be operated.

The upper end of the actuating rod 56 slidably 60 receives an insulating collar 56' which is rigidly mounted on a bimetallic thermostatic switch arm 57. The thermostat 57 is positioned to be responsive to the temperature of the air in the refrigerating compartment. A small cushioning spring 58 is interposed between the insulating collar 56' and an enlarged head 59 on the extreme upper end of the actuating rod 56. The bimetallic thermostat 57 is the box temperature control switch for the apparatus and will be described more fully hereinafter.

An ice-freezing control is also provided and operates in conjunction with the box cooling control previously described. The ice-freezing control comprises a bimetallic thermostat 60 which

is mounted in thermal contact with one of the ice-freezing pads 39, or 40, or in thermal contact with the water vessel 42 closely adjacent to an ice-freezing pad.

Power is supplied to the control mechanism from a line wire 61 directly to a U-shaped electrical contact 60' which is mounted on and insulated from the bimetallic element 60. The bimetallic element 60, which is responsive to the demand for refrigeration at the ice-freezing portion of the evaporator, is positioned to cause the member 60' to contact an electrical contact 62 when a block of ice has formed on the inside of the water tank 42. This will occur at a relatively low temperature such as, for example, 20 or 25 degrees Fahrenheit. The contact 62 is connected by means of a wire 63 to the thermostatic switch 51. The box temperature responsive thermostat 57 is adapted to close the circuit through an electrical contact 64 which is connected by means of a wire 65 to a wire 66 leading to the solenoid valve 44. The wire 66 is also connected to a contact 67 which is positioned to be contacted by the contact 60' on the thermostatic element 60 under conditions to be described hereinafter. The solenoid gas valve 44 is connected by means of a wire 68 to a solenoid coil 69 which is positioned to attract a magnetic armature 56' carried by the lower end of the actuating arm 56. The solenoid coil 69 is connected by means of a wire 70 to a contact 71 which is positioned to be contacted by the contact 60' simultaneously with the contact 67. The wire 68 is also connected to the line wire 72.

The operation of this form of the invention will now be described. Assuming that the machine has been out of operation and that the air temperature in the box and the temperature of the ice-freezing portion of the evaporator are such as to create a demand for refrigeration, the thermostat 57 will be flexed upwardly whereby to open the flap valves 48 and 49 in order that the air within the box may have its temperature lowered by contact with the box cooling coil 31. However, under these conditions the thermostatic element 60 has shifted to the left as viewed in Figure 1 and is closing the circuit through the contacts 67 and 71. The current then flows from the line 61 through the contact 60', the contact 71, the wire 70, the solenoid coil 69, the wire 68 and back to the line wire 72. Current also flows from the switch contact 60' through the contact 67, the wire 66, to the solenoid valve 44 and from the solenoid valve 44 through the wire 68 to the line wire 72. Energization of the solenoid coil 69 overcomes the tension of the bimetallic thermostat 57 against the cushion spring 58 and pulls the actuating rod 56 downwardly to effect closure of the flap valves 48 and 49. Energization of the solenoid valve 44 causes a flame to be carried on the burner 25. As a result of this action, refrigerant liquid is discharged from the conduit 14 into the evaporator box-cooling coil 31. Due to the fact that the box-cooling coil is completely enclosed in the insulating casing 41 and the flap valves 48 and 49 are closed, no refrigeration can take place in this coil except a small amount necessary to lower the temperature to such a point that the refrigerant liquid will no longer evaporate into the inert gas. After lowering the temperature of the box-cooling coil, the refrigerant liquid discharges into the inlet 33 of the ice-freezing coils of the evaporator. Refrigeration then takes place in the coils 34, 35, 36, 37 and 38 whereby ice is frozen on the inner surface of

those portions of the water tank 42 in direct contact with the freezing pads 39 and 40.

Ice freezing continues until the ice blocks formed within the tank 42 have reached such thickness that the heat transfer therethrough to the pads 39, or 40, has reached such a low value that the temperature of the ice-freezing coils of the evaporator reaches a very low value. When the temperature of the ice-freezing coils of the evaporator has reached a very low value the thermostat 60 flexes to the right, as viewed in Figure 1, thereby de-energizing the solenoid coil 69 and the solenoid valve 44.

When the ice blocks have formed on the ice-freezing coils and the thermostat 60 has moved to the right, as viewed in Figure 1, the contact 60' contacts the electrical contact 62. Current now flows from the line 61 through the contact 60', contact 62, wire 63, bimetallic thermostatic switch element 57, contact 64, wire 65, wire 66, to the solenoid valve 44. Current flows through the solenoid valve 44 through the wire 68, and line wire 72 as before. It will be seen that under these conditions the solenoid coil 69 is de-energized and the bimetallic switch element 57 is flexed upwardly to cause the actuating rod 56 to open the flap valves 48 and 49. The air in the refrigerating compartment is now able to reach the box-cooling coil with the result that the temperature of the coil is very rapidly raised and the refrigerant liquid supplied thereto from the conduit 14, instead of simply passing into the ice-freezing coils, evaporates into the inert gas flowing upwardly through the box-cooling coils and produces refrigeration therein. Due to the fact that refrigerant liquid is no longer supplied to the ice-freezing coils of the evaporator the ice blocks formed adjacent the freezing parts 39 and 40 melt free from the metal surfaces of the vessel 42 and float to the surface of the water therein contained. Melting of the ice blocks is accelerated due to the fact that the freezing pads, ice-freezing coils, and water tank are in direct contact with the air in the food compartment.

The box-cooling coil continues to produce refrigeration until the temperature of the air within the box has reached the value for which the thermostat 57 is set whereupon the thermostat 57 flexes downwardly, as viewed in Figure 1, and causes the actuating rod 56 to close the flap valves 48 and 49. If the ice blocks should melt free before the box-cooling coil has reduced the temperature of the air in the refrigerator to the value for which the thermostat 57 is set, the thermostat 60 will shift to the left, as viewed in Figure 1, and energize the solenoid valve and the solenoid coil 69 in the manner previously described thereby producing refrigeration in the ice-freezing coils and causing closure of the flap valves 48 and 49 irrespective of the position of thermostat 57.

Thus it will be seen that I have provided a refrigeration control mechanism so arranged that the demand for ice takes precedence over demand for box cooling and in which a control responsive to demand for ice and another control responsive to demand for refrigeration in the food preserving portions of the box are properly interrelated to achieve the desired results.

It is believed that the following table will make the operation of my control apparatus perfectly clear. In this table column A represents the temperature of the ice-freezing pads 39 and 40. For purpose of illustration, it is assumed that the contact 62 is made when the pads reach a

temperature of 25 degrees Fahrenheit and that the contacts 67 and 71 are made when the ice-freezing pads reach a temperature of 33 degrees Fahrenheit. Also for purpose of illustration, it is assumed that the thermostat 57 makes the contact 64 when the temperature of the air and the box reaches 45 degrees or exceeds that figure. Column B represents box temperature. Column C indicates the electrical contacts made by the switch contact 60'. Column D indicates whether or not the circuit is closed through the contact 64. Column E indicates the condition of the flap valves 48 and 49. Column F indicates the condition of the solenoid gas valve 44. Column G represents the condition of the solenoid coil 69.

A	B	C	D	E	F	G
33	>45	67 71	Open	Closed	Open	Energized
25	>45	62	Closed	Open	do	De-energized
33	<45	67 71	Open	Closed	do	Energized
25	<45	62 do	do	Closed	do	De-energized

It is believed that the above table clearly indicates the control exercised by the two controlling switches. It is to be noted that demand for ice takes precedence over demand for box-cooling at all times.

The above described control mechanism is self-defrosting; that is, the frost which forms on the ice-freezing portions of the evaporator automatically melts therefrom during the period when these portions of the evaporator are inoperative in order to release the ice blocks frozen inside the vessel 42. A minute amount of frost may form upon the box cooling coil during the time when the flap valves 48 and 49 are closed due to the slight amount of moisture contained in the air entrapped within the insulating box 47. However, this frost will melt as soon as the machine operates to cool the box, and at this time there will be no frost deposition on the coil 31 or fins 32 due to the fact that their temperature is not sufficiently low to freeze moisture from the air. It will be seen that there is a continuous formation of frost and a melting thereof; therefore some means must be provided to eliminate this moisture continuously and automatically.

I have illustrated one means of disposing of the frost drainage in Figure 3. The drainage system includes a pan 73 which is positioned entirely beneath the box cooling and ice freezing portions of the evaporator. Any drippage from any portion of the evaporator is caught in the pan 73 and is discharged through a conduit 74 to the chimney 12 of the boiler B. That portion of the chimney 12 which extends above the shell 11 is provided interiorly thereof with a coiled wire 75 which is positioned to intercept liquid draining through the conduit 74. The wire coil 75 causes the drainage to spread over the large area of the coil and to be evaporated rapidly by the exhaust gases from the burner 25. The pilot flame carried on the burner 46' is sufficient to evaporate any drainage occurring at this time.

It will be understood that the disclosure in Figure 1 is diagrammatic. Preferably the apparatus will be applied to an insulated refrigerating cabinet with the boiler, absorber, absorber cooler, and condenser positioned beneath the refrigerating compartment or rearwardly thereof. The heat exchanger is preferably imbedded in

the insulation in the back wall of the refrigerating compartment and the conduits 15, 20, 14, and 14 pass through the rear wall of the refrigerating compartment. It will be understood that the present disclosure is diagrammatic and that the thermostatic control mechanism and the actuating mechanism will be arranged in the refrigerator to be hidden from view.

10 Referring now to Figure 4 there is disclosed a modification of the control apparatus illustrated in Figure 1. It will be understood that the refrigerating system, with the exception of the control mechanism now to be described, may 15 be identical with that disclosed in connection with Figure 1. For purposes of convenient comparison, the evaporator box-cooling coil, the freezing coil, the freezing pads, the water vessel, the box-cooling coil casing, the flap valves, and 20 the connecting linkage for the flap valves will be provided with the reference characters utilized for identical parts in Figure 1.

A short actuating arm 56 is connected at one end to a resilient operating arm 101 of a magnetic toggle mechanism 109 and is pivotally connected at its opposite end at 55 to an extension of the flap valve 49 which is connected with the flap valve 48 by a link 52 in a manner previously described whereby the flap valves are operated 30 simultaneously.

This form of the invention is designed to freeze ice blocks within a containing vessel 42 in the same manner in which the invention of Figure 1 operates. Only the evaporator sections 34 and 35 are illustrated in Figure 4 though it will be understood that the evaporator is identical with that disclosed in Figure 1. The ice-freezing pads 39 are identical with those disclosed in Figure 1.

Gas is supplied to a gas burner similar to that disclosed in connection with Figure 1 from a conduit 102, an "on" and "off" valve 103, and a conduit 104. The valve 103 is provided with a slotted actuating arm 105 which receives a pin 106 mounted on the end of a resilient actuating arm 107 of a magnetic toggle mechanism 108. An over-center snap spring 150 is rigidly connected at one end to any suitable fixed support 151. It will be understood that any suitable toggle linkage may be utilized.

50 Power is supplied to the apparatus from a line 110 which is connected to the fixed end 111 of toggle arm 107. The toggle arm 107 is mounted so that it will contact a resilient switch contact 112 when the gas valve 103 is in the open position and will contact a resilient switch contact 113 when the gas valve 103 is in the closed position. The switch contact 112 is connected by means of a wire 114 to the solenoid coil 115 which in turn is connected by means of a wire 116 to a switch contact 117. The switch contact 113 is connected by a wire 118 to a solenoid coil 119 which is connected by means of a wire 120 to a contact 121 and to a contact 122. It will be noted that the switch contacts 112 and 113 are positioned to energize solenoid coils, which will urge the arm 107 in a direction to break the circuit through the switch contact in engagement with the arm 107. The resilient switch contacts are positioned to maintain the circuit until the spring 150 has snapped over center.

70 The solenoid coils 115 and 119 are provided with iron cores 126 and 127, respectively. These iron cores are positioned to attract a soft iron plug 128 suitably mounted in the actuating arm

101 and insulated therefrom by any suitable means not shown.

The contacts 117 and 121 are adapted to be contacted by a bimetallic thermostatic switch blade 123 which is connected by a wire 124 to a contact 125. The bimetallic member 123 is positioned to be responsive to the temperature of the air in the box and corresponds to the thermostat 57 previously described.

When the temperature of the box exceeds a given predetermined value, 45 degrees for example, the circuit is made through the contact 121. When the temperature of the box drops below the predetermined temperature the circuit is made through the contact 117. The operation of this switch in conjunction with the remainder of the control apparatus will be more fully described hereinafter.

Power is also supplied through the line 147 to a U-shaped contact 131 which is mounted in insulating material 132 carried on the free end of a bimetallic thermostat 129. The bimetallic thermostat 129 is rigidly mounted on a block 130 of material having a high heat conductivity and in good thermal contact with the ice-freezing evaporator coils 34 and 35 whereby the bimetallic thermostat 129 responds to temperature conditions of the ice-freezing coils. In the right hand position of the thermostat 129, as viewed in Figure 4, the contact 131 engages the contact 122, 10 previously described, and a contact element 133. In the left hand position of the thermostat 129, as viewed in Figure 4, the contact 131 engages the switch contact 125, previously described, and a switch contact 34. The contact 133 is connected by a wire 135 to a solenoid coil 136 which is connected by wire 137 to a resilient switch contact 138. The switch contact 134 is connected by a wire 139 to a solenoid coil 140 which is connected by a wire 141 to a resilient switch contact 142. The actuating toggle arm 101 is connected by a wire 143 to the line wire 110.

The free end of the toggle arm 101 is provided with a pin 152 which is engaged in the end slot of a toggle arm 153 which is pivotally mounted at 154 on a suitable fixed support. A toggle spring 155 is connected at its ends to a fixed support 156 and to the free end of the toggle arm 153.

The solenoid coils 136 and 140 are provided with iron cores 144 and 145, respectively. These iron cores are adapted to attract a soft iron armature 146 which is suitably mounted in the arm 101 and suitably insulated therefrom by means not shown.

The resilient contacts 138 and 142 are arranged to maintain contact with the actuating arm 101 until it has moved the spring 155 past the pivot point of the arm 153. Each of the contacts 138 and 142 is connected to a solenoid coil which operates to urge the actuating arm in a direction to break the circuit between the contact and the arm 101. For example, if the arm 101 is in engagement with the contact 142, energization of the wires 139 and 143 will cause energization of the solenoid coil 140 through the contact 142 and the arm 101. Under these conditions the arm 101 will be snapped upwardly, as viewed in Figure 4, and will deenergize the coil 140 by breaking the contact between 142 and 101.

The operation of this form of the invention will now be described. Assuming that the machine is entirely out of operation and that the box temperature exceeds the temperature for which the thermostat 123 is set, for example, 45 degrees, and that the water within the tank 42

is warm, it will also be assumed that the gas valve is closed and that the flap valves 48 and 49 are open. The thermostatic element 129 will then be moved to the right, as viewed in Figure 4, and will make contact with switch contacts 122 and 133. The bimetallic element 123 will be flexed upwardly to close the circuit through contact 121, as viewed in Figure 4. As a result of these conditions power will be supplied from the line 110 to the magnetic toggle arm 101, contact 113, wire 118, solenoid coil 119, wire 120, contact 122, and contact 131 to the line 147. This will energize the gas valve controlling magnetic toggle in such fashion that the gas valve is moved to the open position and the circuit is broken at the contact 113. Power will be supplied from the line 110 through the wire 143, the magnetic toggle arm 101, contact 138, wire 137, solenoid coil 136, wire 135, contact 133, and contact 131 to the line 147. This action will shift the magnetic toggle mechanism 101 into position to close the flap valves 48 and 49 even though the bimetallic element 123 be in a position to demand refrigeration for the box.

The condition just described will continue until a sufficient quantity of ice has formed on the inside wall of the vessel 42 whereupon the bimetallic element 129 will flex to the left, as viewed in Figure 4, and will close the circuit through contacts 134 and 125. If the arm 123 is still in a position to demand refrigeration for the air within the refrigerator box, the gas valve will remain in the position to which it was initially urged. Assuming a demand for refrigeration for the air in the box, power will be supplied through the line 110, the wire 143, the arm 101, the contact 142, the wire 141, the solenoid coil 140, wire 139, contact 134 and contact 131 to the line 147. This will shift the magnetic toggle arm 101 upwardly as viewed in Figure 1 with the result that the flap valves 48 and 49 will be open to permit the air in the box to circulate freely over the box cooling coil 31 and the fins 32, and the circuit will be broken by disengaging the contact 142 and the arm 101 after the toggle has snapped over center.

The condition just described will continue until such time as the box temperature shall have reached the predetermined value whereupon the bimetallic thermostat 123 will flex downwardly, as viewed in Figure 4, and close the circuit through the contact 117. Power will now be supplied through the line 110, toggle arm 101, contact 112, wire 114, solenoid coil 115, wire 116, contact 117, bimetallic element 123, wire 124, contact 125, and contact 131 to the line 147.

If the ice blocks should entirely free themselves before the box temperature reaches the value for which the thermostat 123 is set, the thermostat 129 will shift to the right, as viewed in Fig. 4, and cause closure of the flap valves 48 and 49 regardless of the position of the thermostat 123.

It is believed that the following table will make clear the operation of this form of the invention. In this table column A represents the temperature of the ice freezing coils. For purposes of illustration it is assumed that the contacts 122 and 133 are made when the temperature reaches 33° F. and that the contacts 125 and 134 are made when the temperature reaches 25° F. Column B represents the temperature of the air in the box. For purposes of illustration it is assumed that the contact 121 is made when the temperature exceeds 45° F. and that the con-

tact 117 is made when the temperature falls below 45° F. Column C indicates the contacts made by the contact 131. Column D indicates the contacts made by the thermostat 123. Column E indicates the condition of the flap valves 48 and 49. Column F indicates the condition of the gas valve.

A	B	C	D	E	F
33	>45	{ 122 133 }	121	Closed	Open
33	<45	{ 122 133 }	117	...do...	Do.
25	<45	{ 125 134 }	117	Open	Closed
25	>45	{ 125 134 }	121	...do...	Open

It will be noted that in this form of the invention power is utilized only to shift the various valves from one position to another; there is no continuous consumption of electrical energy.

Figure 5 illustrates the arrangement of the freezing elements in the cabinet. The controls, conduits, and other parts of the system are omitted for clarity. It will be noted that the water tank 42 conceals the insulating box 47 and that it may be slid forwardly on the freezing pads for removal from the cabinet 200.

A few advantages and useful functions which naturally flow from both forms of the invention described are worthy of note. Due to the fact that the water in the tank 42 is constantly exposed to circulating air in the refrigerating compartment the humidity of the air within the compartment is maintained at a relatively high value. If desired the water tank 42 can be provided with a cover to prevent contamination of the contents of the vessel and to reduce heat loss therefrom. This does not impair the humidifying properties of the water tank as the cover will not be sealed. The frost drainage collecting in the pan 73 is a further factor in maintaining a high humidity within the refrigerating compartment.

By reason of the fact that the individual blocks of ice float freely in a body of very cold water, the housewife need not take out a large number of ice cubes at one time; any number of cubes, from one to the maximum capacity of the unit, may be ladled out of the water tank 42 as desired. This arrangement of the formation of ice cubes eliminates the necessity for trays, grids, and special ice cube releasing mechanisms.

The water tank 42 may be provided with a spigot 175 whereby fresh cold drinking water is available at all times.

When the water tank is exposed to the air in the box it acts as a thermal flywheel due to its large heat capacity. That is, the large body of cold water and ice in the tank prevents excessive temperature changes in the air in the box.

By reason of the readily removable mounting of the vessel 42 upon the ice-freezing evaporator coils, it is a very simple matter to remove this element to facilitate cleaning of the vessel 42, or other parts of the refrigerating compartment. The ready removability of the vessel 42 also facilitates the process of adding water thereto. For example, when it is desired to add water to the vessel 42, it may be slid forwardly on the ice-freezing coils without being removed therefrom until the forward end of the vessel 42 projects outwardly of the refrigerating compartment. In this position it is a very simple matter to pour water into the vessel 42 from a kettle or other

suitable carrier. The ice-freezing coils may be made deep enough to prevent the vessel 42 from over-balancing when pulled outwardly beyond the front opening of the refrigerating compartment.

A door 201 is shown in the top portion of the refrigerating cabinet. This provides an alternate means of supplying water to the tank 42 and of removing ice blocks from the tank. The top door has the advantage that it is not necessary to open the storage compartment door in order to obtain access to the freezing tank. Also the door 201 does not permit the cold air in the box to escape when ice is removed from the freezing tank.

While I have described several embodiments of my invention, it is to be understood that the invention is capable of embodiment in other constructional forms without departing from the invention or the scope of the appended claims.

I claim:

1. A refrigerating system including an evaporator having distinct box-cooling and ice-freezing sections, said sections being arranged so that liquid refrigerant supplied to the top portion of the box-cooling section may flow downwardly through the entire evaporator by gravity, means for supplying an inert gas stream to the lowest portion of the evaporator, and means responsive to demands for refrigeration operative to cause evaporation of the liquid refrigerant into the inert gas stream to occur in a selected one of said sections.

2. A refrigerating system including an evaporator, means for supplying liquid refrigerant to said evaporator, means for supplying a pressure equalizing medium to said evaporator, and means operative to cause substantially all the liquid refrigerant to evaporate into the pressure equalizing medium in a selected section of said evaporator.

3. A refrigerating system including an evaporator having a vertically positioned box-cooling coil and an ice-freezing coil positioned therebelow, a casing enclosing said box-cooling coil, valves in said casing arranged to permit or to prevent flow of air therethrough, and means operative to open said valves in response to a demand for box-cooling.

4. That improvement in the art of absorption refrigeration which includes the steps of conducting a stream of pressure equalizing medium through a path in heat exchange relation with material to be frozen and then through a path in heat exchange relation with a fluid to be cooled, supplying refrigerant to be evaporated to said path, and controlling the area of evaporation in such manner that substantially all the evaporation occurs in one path or the other.

5. An evaporator for refrigerating systems comprising a vertically positioned coil provided with fins, a pair of spaced horizontally positioned, reversely bent, coil sections connected together in series and connected to said vertically positioned coil, and a plurality of freezing pads mounted upon said horizontal coil sections whereby they are adapted to receive a vessel containing water to be frozen.

6. A refrigerating system comprising a boiler, a condenser, an evaporator, and an absorber connected in circuit to provide a continuous absorption refrigerating system, a water tank positioned in heat exchange relationship with said evaporator, and means for causing evaporation to occur within said evaporator for a sufficient

period of time to form an ice block within said water container and to thereafter render said evaporator inoperative for a period of time sufficient to permit said ice blocks to melt free of the wall of said container.

7. That improvement in the art of refrigeration which includes the steps of generating vaporous refrigerant, liquefying the refrigerant, vaporizing the refrigerant in the presence of a pressure equalizing medium in order to produce refrigeration characterized by the fact that the said evaporation occurs in a zone in heat exchange relationship at a plurality of points with a large body of water whereby a plurality of blocks of ice are formed in said body of water, continuing evaporation until blocks of a predetermined size have been formed, discontinuing evaporation in heat exchange relationship with said plurality of points and producing evaporation in a zone in heat exchange relationship with a medium to be cooled.

8. Refrigerating apparatus comprising a generator, a gas burner positioned to heat the generator, a solenoid valve controlling said gas burner, a condenser, an evaporator comprising separate box-cooling and ice-freezing sections, an insulating box provided with a pair of flap valves enclosing said box-cooling section, a thermostatic mechanism adapted to move said flap valves to open and closed position, means whereby said thermostatic mechanism energizes said solenoid valve when it moves said flap valves to open position, thermostatic mechanism responsive to refrigeration demand by said ice freezing section, means whereby said second mentioned thermostatic mechanism is operative to energize said solenoid valve, and means energized simultaneously with the solenoid valve by said second thermostatic mechanism operative to force said flap valves to closed position irrespective of the position of said first mentioned thermostat.

9. Refrigerating apparatus including means controlling the supply of energy thereto, an evaporator having box cooling and ice freezing sections, means constructed and arranged to allow or prevent flow of air over said box cooling section, magnetic means for controlling said air flow control means, magnetic means for controlling said energy supply control means, means responsive to box temperature operative to energize said second mentioned magnetic means to permit or to prevent energy supply in accordance with the demand for box cooling, and means for energizing said magnetic means to prevent air flow over said box cooling coil and to supply energy in response to a demand for ice freezing and operative to energize said first mentioned magnetic means to allow air flow over said box-cooling coil whenever there is no demand for ice freezing.

10. An absorption refrigerating system comprising an evaporator having a plurality of sections, means for supplying refrigerant liquid and a pressure equalizing medium to said evaporator, means adapted to isolate one section of said evaporator thermally to prevent evaporation of refrigerant therein, means responsive to a condition produced by another section of said evaporator for controlling said refrigerant supply means and said isolating means, and means responsive to a condition produced by said one section of said evaporator for controlling said isolating means and said refrigerant supply means when said first mentioned condition responsive means has operated in a predetermined manner.

11. A refrigerating system including an evaporator having distinct box-cooling and ice-freezing sections, said sections being arranged so that liquid refrigerant supplied to the top portion of the box-cooling section may flow downwardly through the entire evaporator by gravity, means for supplying an inert gas stream to the lowest portion of the evaporator, and thermostatically actuated control means responsive to refrigeration demand for forcing the refrigerant to evaporate in a selected section of said evaporator and for subordinating the refrigerating requirements of one of said sections to the refrigerating requirements of another of said sections.
- 15 12. That improvement in the art of absorption refrigeration which includes the steps of conducting a stream of pressure equalizing medium through a path in heat exchange relation with material to be frozen and then through a path in heat exchange relation with a fluid to be cooled, supplying refrigerant to be evaporated to said path, evaporating substantially all the refrigerant in whichever one of said paths is in heat exchange relation with material requiring refrigeration, and producing refrigeration in a selected one of said paths whenever there is a demand therefor without regard to the refrigerating requirements of the other of said paths.
- 20 13. A refrigerating system including an evaporator having a vertically positioned box-cooling coil and an ice-freezing coil positioned therbelow, a casing enclosing said box-cooling coil, valves in said casing arranged to permit or to prevent flow of air therethrough, means operative to open said valves in response to a demand for box-cooling, and means for preventing operation of said flap valves when there is a demand for refrigeration in said ice-freezing coil.
- 25 14. Refrigerating apparatus including an evaporator having a plurality of serially connected sections, means for supplying refrigerant liquid and a pressure equalizing medium to said evaporator, means responsive to a first condition for rendering said supply means operative and for substantially preventing evaporation of refrigerant into the pressure equalizing medium in one section of said evaporator, means responsive to a second condition for rendering said supply means operative and for conditioning said one section to allow evaporation of refrigerant therein provided said section is not rendered inoperative by said first mentioned condition responsive means.
- 30 15. A refrigerating system comprising a boiler, a condenser, an evaporator, and an absorber connected in circuit to provide a continuous absorption refrigerating system, a water tank positioned in heat exchange relationship with a portion of said evaporator, and means for causing evaporation to occur within said portion of said evaporator for a sufficient period of time to form an ice block within said water container and to thereafter render said portion of said evaporator inoperative for a period of time sufficient to permit said ice block to melt free of the wall of said container, and means for causing evaporation to occur within another portion of said evaporator during the ice melting period if there is a demand therefor.
- 35 16. Refrigerating apparatus including a plurality of evaporators, an absorber, means for supplying liquid refrigerant to said evaporators, means forming a pressure equalizing medium circuit including said absorber and said evaporators,
- 40
- 45
- 50
- 55
- 60
- 65
- 70

said pressure equalizing medium circuit being constructed and arranged to cause circulation of said pressure equalizing medium by factors wholly within the system, and temperature responsive means for causing substantially all of said liquid refrigerant to evaporate into said pressure equalizing medium in a selected one of said evaporators.

17. A refrigerating system including a generator, a heater for said generator, a heat discharge flue for said heater, an evaporator, control means constructed and arranged to cause said evaporator to operate at temperatures above and below the melting point of ice, means positioned to collect the drainage from frost melting from said evaporator, and means for conducting said drainage into said exhaust flue.

18. A refrigerating system including a generator, a heater for said generator, a heat discharge flue for said heater, an evaporator, control means constructed and arranged to cause said evaporator to operate at temperatures above and below the melting point of ice, means positioned to collect the drainage from frost melting from said evaporator, means for conducting said drainage into said exhaust flue, and means within said flue constructed and arranged to spread said drainage in a thin film over an extended surface area.

19. Refrigerating apparatus comprising an evaporator having distinct box-cooling and ice-freezing sections, a water container in heat transfer relationship with said ice-freezing section at a plurality of spaced points whereby a plurality of separated blocks of ice are formed on the inner wall of said container whenever said ice-freezing evaporator section is operative, and control means operative to cause evaporation to occur within said ice-freezing evaporator section for a period of time sufficient to produce blocks of ice of a predetermined dimension within said water compartment and to render said ice-freezing evaporator section inoperative thereafter for a period of time sufficient to permit said ice blocks to melt free of the inner wall of said water vessel and to float to the surface of the water contained therein, said control means also being operative to allow substantial evaporation to occur within said box-cooling coil only during those times when there is no demand for evaporation to produce ice and there is a demand for box cooling.

20. A refrigerating system including an evaporator having distinct box-cooling and ice-freezing sections, means for supplying energy to said system, means responsive to box temperature adapted to render said box-cooling element operative or inoperative in accordance with the demand for box cooling and to render said energy supply means operative, means responsive to the demand for ice freezing and adapted to render said energy supply means operative or inoperative and to render said box cooling coil inoperative regardless of the demand for box cooling whenever said last mentioned means has rendered said energy supply means operative.

21. Refrigeration apparatus comprising an evaporator having separate box-cooling and ice-freezing sections, an insulating box enclosing said box-cooling section, a pair of flap valves pivotally mounted on opposite ends of said box to control flow of air over said box-cooling coil, a thermostat positioned to be responsive to the temperature of the air in the box and adapted to move said flap valve to open or closed position,

a thermostat responsive to the demand for ice-freezing and adapted to condition the system to produce refrigeration, and means energized by said ice demand thermostat operative to close said flap valve.

22. Refrigerating apparatus including means controlling the supply of energy thereto, an evaporator including box-cooling and ice-freezing sections, an insulating casing enclosing said box-cooling section, valve means mounted on said insulating casing adapted to allow or prevent flow of air over said box-cooling section, a reciprocably mounted arm connected to cause opening or closing of said valve means, a thermostat positioned to be responsive to the temperature of the air in the box for operating said reciprocably mounted arm, a circuit closed by said thermostat when it has moved said valve means to open position and to operate said energy supply control means to energy supply position, a thermostat mounted to be responsive to the temperature of said ice-freezing section, a circuit closed by said second mentioned thermostat in response to demand for ice-freezing operative to condition said energy supply control means to supply energy to the refrigerating apparatus and including a solenoid coil surrounding said reciprocating arm and operative to cause closure of said valve means when energized independently of the condition of said first mentioned thermostat.

23. Refrigerating apparatus comprising means controlling the supply of energy thereto, an evaporator including ice-freezing and box-cooling sections, means adapted to allow or prevent flow of air over said box-cooling section, magnetic means operative to actuate said air-flow control means, magnetic means operative to actuate said energy supply means, means responsive to the temperature of said ice-freezing section operative in one position to energize said first mentioned magnetic means to cause closure of said air-flow control means and to energize said second mentioned magnetic means to cause supply of energy to the apparatus, and operative in another position to cause opening of said air-flow control means, and means responsive to the temperature of the air in the box operative in one position to energize said second mentioned magnetic means to supply energy to said system and operative in another position to energize said second mentioned magnetic means to discontinue supply of energy to said system.

24. Refrigerating apparatus comprising an evaporator constructed and arranged to support a large tank containing water, and means operative to cause refrigeration to occur in said evaporator for a sufficient period of time to freeze ice blocks on the interior of those portions of said water tank in contact with said evaporator and further operative to prevent refrigeration in said evaporator for sufficient periods of time to permit said ice blocks to melt free of the side wall of said tank and to float to the surface of the water therein contained, a second evaporator, and means for rendering said second evaporator operative to cool air when said first-mentioned evaporator is inoperative.

25. Absorption refrigerating apparatus including a generator having an exhaust gas flue, and an evaporator, a gas burner positioned to heat said generator, a pilot burner for said gas burner also positioned to heat said generator, control means constructed and arranged to control the supply of fuel to said burner in response to de-

mands for refrigeration, means for collecting melted frost dripping from said evaporator, and means for conducting said drainage to said flue whereby it is evaporated either by said main burner or by said pilot burner depending upon whether or not said main burner is operating.

26. Refrigerating apparatus comprising an evaporator having a vertically positioned box-cooling coil and a horizontally positioned ice-freezing coil extending laterally from the lower portion of said box-cooling coil, freezing pads on said ice-freezing coil, a water tank constructed and arranged to be mounted upon said freezing pads in such manner that it substantially conceals said box-cooling coil and may be removed from said ice-freezing coil by being lifted upwardly therefrom or slid forwardly thereof.

27. Refrigerating apparatus comprising a refrigerating compartment, a finned coil positioned in said compartment to be swept by air current therein, an open ended box of insulating material surrounding said coil, a pair of flap valves on opposite ends of said box positioned to open in opposite directions, means connecting said flap valves for simultaneous movement in opposite directions whereby they are counterbalanced, and means responsive to box temperature operative to open and close said flap valves.

28. Refrigerating apparatus including an evaporator having distinct box-cooling and ice-freezing evaporator sections, means operative to allow or to prevent flow of air over said box-cooling section, and means responsive to air temperature operative to control said air-flow control means.

29. Absorption refrigerating apparatus comprising a solution circuit including a boiler and an absorber, an inert gas circuit including an evaporator and said absorber, means for supplying refrigerant vapor produced in said boiler to said evaporator in liquid phase, and control means for selectively restricting the production of refrigeration to a portion of said evaporator.

30. Absorption refrigerating apparatus comprising a solution circuit including a boiler and an absorber, an inert gas circuit including an evaporator and said absorber, means for supplying refrigerant vapor produced in said boiler to said evaporator in liquid phase, and control means for selectively restricting the production of refrigeration to any one of a plurality of portions of said evaporator which is subject to a refrigeration demand, said control means being arranged to confine the refrigerating effect to a selected one of said portions of said evaporator whenever there is a demand therefor to the exclusion of refrigerating demands from other portions thereof.

31. Absorption refrigerating apparatus comprising a solution circuit including a boiler and an absorber, an inert gas circuit including an evaporator and said absorber, means for supplying refrigerant vapor produced in said boiler to said evaporator in liquid phase, means for substantially preventing or allowing the absorption of heat by one portion of said evaporator and control means for operating said heat absorption regulating means in accordance with the demand for refrigeration.

32. Absorption refrigerating apparatus comprising a solution circuit including a boiler and an absorber, an inert gas circuit including an evaporator and said absorber, means for supplying refrigerant vapor produced in said boiler to said evaporator in liquid phase, said evaporator comprising a plurality of sections all connected

5 to allow the inert gas to flow therethrough, said sections being arranged for serial flow of the refrigerant liquid therethrough, means adapted to allow or prevent material absorption of heat by selected portions of said evaporator and refrigeration demand responsive means for controlling said heat absorption allowing or preventing means.

10 33. Refrigerating apparatus including an insulated storage compartment, a cooling unit having a plurality of sections within said insulated compartment, means for supplying a cooling medium to said cooling unit, means adapted to prevent substantial absorption of heat by one of said sections of said cooling unit, and refrigeration demand responsive means for operating said heat absorption preventing means.

15 34. Refrigerating apparatus including an insulated storage compartment, a cooling unit having a plurality of sections within said insulated compartment, means for supplying a cooling medium to said cooling unit, means adapted to prevent substantial absorption of heat by one of said sections of said cooling unit, refrigeration demand responsive means for operating said heat absorption preventing means, said refrigeration demand responsive means being constructed and arranged to place said heat absorption preventing means in heat absorption preventing condition

20 30 whenever there is a demand for refrigeration by the section of said evaporator not directly affected thereby.

35 35. In a refrigerating apparatus, a cabinet structure including an insulated storage chamber, a cooling unit positioned in said storage chamber, said cooling unit including a plurality of sections, means for supplying a refrigerant liquid to said cooling unit, means for supplying an inert gas to said cooling unit, and means for controlling the temperatures of said sections of said cooling unit including means operative to inhibit and promote absorption of heat by one of said sections whereby the temperature of another of said sections rises when absorption of heat and evaporation of the liquid refrigerant by said one section of said cooling unit is promoted and the temperature of said another section of said cooling unit decreases when the evaporation of the liquid refrigerant in said one section is inhibited

40 50 by inhibiting the absorption of heat thereby.

36. In an absorption refrigerating apparatus, an insulated refrigerating compartment, a cooling unit in said compartment, means for conducting an inert gas to and from said cooling unit, means for supplying a refrigerant liquid to said cooling unit, said cooling unit being so arranged in said compartment that air to be cooled will flow thereby in heat transfer relationship but out of contact with inert gas and liquid refrigerant in said cooling unit, and means constructed and arranged to govern the flow of air in contact with a portion of said cooling unit thereby to govern the evaporation of liquid refrigerant in said portion of said cooling unit.

45 37. In a refrigerator, a thermally insulated refrigerating storage chamber, an evaporator having a plurality of sections positioned in said chamber to be contacted by the air therein, an absorber, means connecting said evaporator and said absorber for circulation of inert gas therebetween, means for supplying refrigerant liquid to said evaporator, means for governing the temperatures of said sections of said evaporators including means constructed and arranged to govern the circulation of air in contact with one of

50 75

said evaporator sections, and thermostatic means positioned within said storage chamber for regulating the production of refrigerant liquid and the circulation of inert gas between said evaporator and said absorber.

38. In a refrigerating apparatus, a cabinet structure including an insulated storage chamber, a cooling unit positioned in said storage chamber, said cooling unit including a plurality of sections, means for circulating an inert gas through said cooling unit, means for supplying refrigerant liquid to said cooling unit, the arrangement being such that the inert gas and refrigerant liquid flow in opposite directions through said cooling unit, and means for forcing the liquid refrigerant to evaporate into the inert gas in said sections of said evaporator at a selected temperature level including structure for inhibiting absorption of heat by the section first to receive the refrigerant liquid whereby the temperature of said first section drops and liquid refrigerant flows therethrough into the section first to receive inert gas.

39. Absorption refrigerating apparatus comprising an insulated cabinet including a refrigerating and storage chamber, a refrigerating mechanism associated with said cabinet including an evaporator having an air cooling part and a chilling part positioned within said chamber, an absorber connected to said evaporator for circulation of inert gas therebetween, means for supplying refrigerant liquid to said evaporator, and means to control the evaporation of refrigerant liquid into the inert gas in said air cooling part of said evaporator including means arranged to control the abstraction of heat therefrom to govern the quantity of refrigerant liquid which flows through the air cooling part of said evaporator into the chilling part thereof whereby to control the cooling effect produced by said chilling part.

40. In a refrigerating apparatus, a cabinet structure including an insulated storage chamber, a cooling unit positioned in said storage chamber, said cooling unit including an air cooling section and a chilling section, means for circulating an inert gas through said cooling unit, and means for supplying refrigerant liquid to said cooling unit, the arrangement being such that the inert gas and refrigerant liquid flow in opposite directions through said cooling unit, structure for varying the operating temperature of said chilling unit including structure arranged to promote or restrict evaporation of refrigerant liquid into the inert gas in said air cooling unit whereby the temperature of said chilling unit rises when the evaporation of refrigerant into the inert gas in said air cooling unit is promoted and the temperature of said chilling unit drops when evaporation of refrigerant liquid into the inert gas in said air cooling unit is inhibited.

41. Absorption refrigerating apparatus comprising an insulated cabinet including a refrigerating and storage chamber, a cooling unit positioned in said chamber to refrigerate the air therein, said cooling unit including an air cooling part and a chilling part, means for conducting an inert gas to and from said cooling unit, means for supplying liquid refrigerant to said cooling unit, and means for controlling the production of refrigerant in said parts of said cooling unit including means arranged to govern the absorption of heat therefrom.

42. That method of controlling the production of refrigeration in an evaporator positioned in a

refrigerating storage chamber to be contacted by air flowing in contact therethrough which includes the steps of flowing an inert gas through said evaporator, supplying a refrigerant liquid to said evaporator, and controlling the temperature at which the refrigerant liquid evaporates into the inert gas by controlling the flow of air in heat transfer relationship with said cooling unit.

5 43. A refrigerating system including an evaporator having a plurality of parts, means for supplying a refrigerant liquid to said evaporator, means for substantially isolating one of said parts thermally for preventing the absorption of heat and the production of refrigeration by evaporation of the liquid refrigerant therein, and thermostatic means for controlling said isolating means.

20 44. Ice making apparatus comprising a water container, a cooling unit arranged to refrigerate the contents of said container in a manner to freeze an ice block therein when said cooling unit is operative and to allow a previously frozen ice block to float to the surface of the water in said tank when said cooling unit is inoperative, a generating assembly, means for heating said generating assembly to expel refrigerant vapor therefrom, means for condensing refrigerant vapor expelled from said generating assembly and for supplying the liquefied refrigerant to said cooling unit, and control means constructed and arranged to govern said apparatus to supply liquid refrigerant to said cooling unit to produce refrigeration therein until an ice block has been formed in the water in said tank and to prevent substantial supply of refrigerant liquid to said cooling unit after formation of said ice block until said ice block has floated to the surface of the water in said tank.

25 45. Absorption refrigerating apparatus comprising an evaporator, a container for water arranged in heat transfer relationship with said evaporator, a generator, a condenser connected to receive refrigerant vapor from said generator and to supply refrigerant liquid to said evaporator, means for heating said generator, control means responsive to the thermal condition of said evaporator arranged to govern the energization of said heating means and to condition said apparatus for producing refrigeration for a period of time sufficient to produce an ice block and thereafter to condition said apparatus to discontinue production of refrigeration to permit said ice block to float to the surface of the water in said container.

30 46. In a refrigerating mechanism, a container of water, an evaporator arranged in heat transfer relationship with a small area of said container to freeze an ice block therein of a size small with respect to the volume of said container, heat operated means for producing refrigerant vapor, means for receiving refrigerant vapor from said heat operated means and for supplying refrigerant liquid to said evaporator, and means controlling said apparatus to supply refrigerant liquid to said evaporator to freeze an ice block in said container and for preventing the supply of refrigerant liquid to said evaporator after the formation of said ice block to allow said ice block to float freely to the surface of the water in said container.

35 47. In a refrigerating mechanism, a container of water, an evaporator arranged to refrigerate a plurality of small spaced areas of the wall of said container beneath the surface of the water

therein to produce a plurality of separate blocks of ice in said container, heat operated means for producing refrigerant vapor, means for receiving refrigerant vapor from said heat operated means and for supplying refrigerant liquid to said evaporator, and thermostatic control means arranged to respond to the thermal condition of said evaporator constructed and arranged to govern said apparatus to supply liquid refrigerant to said evaporator to produce ice blocks in the water in 10 said container and to prevent the supply of refrigerant liquid to said evaporator after the formation of said ice blocks to allow said ice blocks to free themselves from the wall of said container and to float to the surface of the water 15 of said container.

48. That improvement in the art of absorption refrigeration which includes the steps of applying heat to a refrigerant absorbed in an absorbing body to liberate refrigerant in vapor phase, conducting the said refrigerant vapor into heat exchange relationship with cooling air to convert the refrigerant vapor to the liquid state, evaporating said refrigerant in the liquid state in heat transfer relationship with one side of a heat conducting wall which is in heat transfer relationship with a body of water to be frozen below the surface thereof, and intermittently discontinuing the evaporation of liquid refrigerant in

heat transfer relationship with said heat conducting wall for periods of time sufficient to allow previously frozen ice to melt out of heat transfer relationship with said heat conducting wall and to float to the surface of said body of water.

5 49. In a domestic refrigerating apparatus, a cabinet structure including an insulated refrigerating chamber, an evaporator positioned in said chamber, a container of water in said chamber arranged in heat transfer relationship with said container at a plurality of points beneath the surface of the water therein, a heat operated refrigerant generator, an air cooled condenser, means for heating said generator, means for conducting refrigerant vapor from said generator to said condenser, means for conducting refrigerant liquid from said condenser to said evaporator, and thermostatic control mechanism arranged to govern said apparatus to supply liquid refrigerant to said evaporator for a period of time sufficient to freeze blocks of ice in said container at said points in heat transfer relationship with said evaporator and thereafter to govern said apparatus to discontinue the supply of liquid refrigerant to said evaporator until previously formed ice blocks have melted free of said points and have floated to the surface of the water in said container.

CURTIS C. COONS.
